UNITED STATES PATENT OFFICE.

CLARENCE E. KRAMER, OF LITHOPOLIS, OHIO.

DESIGN FOR A TROUSERS-HANGER.

SPECIFICATION forming part of Design No. 33,665, dated December 4, 1900.

Application filed April 7, 1900. Serial No. 12,024. Term of patent 7 years.

To all whom it may concern:

Be it known that I, CLARENCE E. KRAMER, a citizen of the United States, residing at Lithopolis, in the county of Fairfield and State of Ohio, have invented and produced a new and original Design for a Trouser-Hanger, of which the following is a specification.

This invention relates to a design for a new and useful trousers-hanger, and in the accompanying drawing I have shown a perspective view thereof.

Referring to said drawing by numerals of reference, 1 is a loop formed at the end of a stem 2, having a spiral 3 therearound, said stem projecting from the center of an oppositely-inclined strip 4, twisted, as shown, and from the free ends of which project, in opposite directions and at right angles to the strip, arms 5, each having a downward extension 6, which is bent upward, as at 7, and thence downward, forming an arm 8, which extends

parallel with and adjacent to the upwardly-extending portion 7 of the extension. This arm 8 is provided with a rounded end 9, as shown. 25

The leading features of the design are the strip 4, having the arms 5 projecting therefrom in opposite directions and at right angles to the strip, the stem 2, coil 3 around the stem, and the extensions 6, 7, and 8. 30

Having thus fully described my design, what I claim as new, and desire to secure by Letters Patent, is—

The design for a trousers-hanger substantially of the form herein shown and described. 35

In testimony whereof I affix my signature in presence of two witnesses.

CLARENCE E. KRAMER.
